No. 758,385.

PATENTED APR. 26, 1904.

W. P. RICE.
CLAMP FOR HOOPS, BANDS, &c.
APPLICATION FILED JULY 28, 1903.

NO MODEL.

UNITED STATES PATENT OFFICE.

GEORGE H. RICKE, OF CINCINNATI, OHIO, ASSIGNOR OF TWO-THIRDS TO
JOSEPH ZIMMERMANN, OF CINCINNATI, OHIO.

BUNG-BUSHING.

SPECIFICATION forming part of Letters Patent No. 758,386, dated April 26, 1904.

Application filed June 20, 1903. Serial No. 162,322. (No model.)

To all whom it may concern:

Be it known that I, GEORGE H. RICKE, a citizen of the United States, residing at the city of Cincinnati, in the county of Hamilton and State of Ohio, have invented certain new and useful Improvements in Bung-Bushings, of which the following is a specification.

The object of my invention is to produce a cheap, simple, and efficient bushing for bungs to be used in beer and other packages for holding liquids.

A further object is to produce a bushing which will prevent the bung-stave from cracking or splitting, the bung-stave being the stave selected to carry the bung and bung-bushing. To accomplish this object, I provide a bushing with an upper and lower screw-thread, a space or cut-away portion without screw-thread being left between the two sets of screw-threads.

The bushing ordinarily used is screw-threaded its entire extent, and when screwed home in the bung-hole the screw-threads grind into the stave and fit very tightly. Every time a beer keg or barrel is returned to the brewery the hoops are pulled down or redriven to take up the shrinkage before it is repitched and filled. This is to prevent leakage. Of course every time the hoops are redriven, and this is a frequent occurrence during the life of the keg or barrel, the staves are more tightly compressed, as is also the head of the keg. Consequently and naturally the keg becomes smaller. The iron bushing of course remains the same size, and the bung-stave being compressed along with its companions assumes a more marked degree of curvature as the hoops are forced down more tightly on the bilge and quarter of the keg. The screw-threads of the bushing press outward against the wood of the stave surrounding the bushing. In this way the stave cracks or splits in the center or outside, producing a leak in time, this necessitating the replacing of a new bung-stave. There is no place for the wood around the bushing to go. It must give with the bushing, and thus is cracked and broken. My new bung-bushing overcomes these defects. I use only about two-thirds of the

amount of screw-threads and leave a space at 50 the center between the bushing and the stave edge, so that when the hoops are redriven I have less pressure against the bushing, and the space allows the wood to adjust itself to the new position around the bushing, preventing cracking and breaking. This space in the bushing also helps to strengthen the stave at the center, where strength is necessary when the keg is being pitched. The immense heat of the pitching-machine is not communicated 55 directly against the wood, as the bushing does not touch it at this place. Great pressure is used in screwing these bushings home, and in this manner the bung-stave is often cracked. I also prevent this, as I cut down the degree 60 of friction between the bushing and the wood when my bushing is inserted.

In the accompanying drawings, forming part of this specification, Figure 1 is a top view of my bushing in the bung-stave, the 70 stave being broken away. Fig. 2 is a central longitudinal section taken at the line X X of Fig. 1, and Fig. 3 a view in elevation of my new bushing. The dotted lines in Fig. 2 show the varying degrees of curvature assumed by 75 the stave incident to the redriving of the hoops.

In the drawings, *a* represents the bung-stave, *b* the bung-hole, and *c* the bung-bushing. The bung-bushing is an annulus or ring widest at 80 the top, where it is surmounted by a flange *d*, and tapering toward the bottom; smooth on the inside. At its periphery the bushing *c* is provided with a series of upper screw-threads *e* and a series of lower screw-threads *g*. These 85 screw-threads encircle its entire periphery. Between these two sets of screw-threads *e* and *g* I provide a plain space or cut-away portion carrying no screw-threads. This space is marked *h*. This space *h* may be as deep as 90 desired, and its extent may be varied. This peculiar formation of the bush prevents the stave from cracking when the hoops are redriven, as before described, allowing the wood to give somewhat, and thus adjust itself. 95

If desired, I may encircle the bottom of the flange *d* with a rib or tongue *k* to assist in tightening the bush in the stave.

so that said end of the band will be permanently secured to the plate. This will cause the clamping-plate to be secured to the end of the band without danger of detachment 5 therefrom, and when it is desired to bind the staves of the cask in position the band is placed around the same and the opposite or free end thereof—in the present instance the end b'—is passed through the slot 12 of the 10 plate 5 and beneath the inwardly-extending teeth or tongues 14 14, cut from the body of the plate in a manner similar to the teeth 13 13, and by the blow of a hammer, mallet, or the like the aforesaid teeth 14 14 may be 15 driven inward through the end of the band, the latter being formed of material which is preferably softer than the material from which the plate of the clamp is formed, so that the teeth 14 14 of the plate may penetrate said 20 band without danger of bending or breaking.

In order to prevent the teeth 13 13 and 14 14 from entering the sides of the cask or engaging therewith in such manner as to prevent the band from being moved downward 25 upon the cask-body to tighten the same, I provide a plate 16, which for the purpose of convenience I shall designate as a "bearing-plate," and this plate is formed with flanges 17 17, designed to fit over the longitudinal 30 portions of the main plate of the clamp, the end portions of the clamp bearing against the shoulders 9 9 and 10 10 of said main plate.

The aforesaid supplemental or bearing plate 16 is provided with an approximately U-shaped cut-away portion 18, and the end of the extending end of the band after passing through the slot in the plate lies next to the cask in the slot portion 18, as clearly seen in Figs. 2 and 3.

40 In Figs. 6 and 7 I have shown a slightly-modified form of tie-clamp, the latter being especially designed for use in securing tie-bands of bales of cotton and the like. In this instance the teeth 19 19 of the plate 7, 45 which are designed to permanently secure the clamping-plate to the band, are turned outwardly, while the opposite set of band-engaging teeth 20 20 are approximately triangular in shape, extend inwardly, and are designed to 50 be driven through the opposite end of the band in such manner that after passing therethrough said teeth will penetrate the cotton-bale and hold the ends of the bands against separation.

55 It will be observed that I have provided an exceedingly simple device for accomplishing the securing of a hoop or band to a cask, bucket, or the like, and one which will hold the staves or parts of the same securely and 60 firmly, while at the same time the size of the band may be adjusted to vessels of varying circumference by pulling the free end of the

band through the slot in the plate until the band is sufficiently tight, when the securing-teeth may be bent to rigidly hold the ends of 65 the hoop or band.

Having thus described my invention, I claim as new and desire to secure by Letters Patent—

1. The combination with a band, of a device for connecting the ends thereof, said device comprising a plate having enlarged end portions, said end portions being each provided with a slot designed to permit the passage of the ends of the band, and teeth formed on the body of the plate and adapted to penetrate the ends of the band passing through said slots, the construction being such that said ends may be firmly connected, and a bearing-plate adapted to be interposed between the band and a cask or the like to which 75 the band is secured, substantially as set forth.

2. The combination with a band, of a device for connecting the ends thereof to form a hoop, said device comprising a plate having slots formed transversely of the end portions 85 thereof to permit the passage therethrough of the free ends of the band, a plurality of teeth arranged adjacent to each of said slots and designed to penetrate the material of the ends of the band for securing the same, and 90 a bearing-plate adapted to engage with the plate and slide over the portions of the band engaged by the teeth, substantially as set forth.

3. A device of the class described, comprising a plate having enlarged end portions, a slot formed transversely of said end portions, said slot being designed to permit the passage of the end of a band, teeth formed from the material of the plate and adapted to penetrate 100 the material of the ends of the band for connecting said ends with the plate, and a bearing-plate formed with flanges adapted to engage with and fit over the relatively narrow longitudinal edge portions of the main plate 105 and to cover the portions of the teeth extending through the band, substantially as set forth.

4. The combination with a cask, bale, or the like, of an adjustable clamping-hoop therefor, said hoop comprising a band portion, a clamping-plate provided with a plurality of teeth designed to connect the ends of the band portion, and a bearing-plate adapted to be interposed intermediate the clamping-plate and 110 the cask, substantially as set forth.

In testimony whereof I have signed my name to this specification in the presence of two subscribing witnesses.
